(57) **CLAIM**

The ornamental design for an evacuation chair, as shown and described.

DESCRIPTION

FIG. 1 is a front perspective view of an evacuation chair showing our new design in a closed position.

FIG. 2 is a front view thereof;

FIG. 3 is a rear view thereof, showing the evacuation chair in an open position;

FIG. 4 is a rear perspective view thereof;

FIG. 5 is a front view thereof; and,

FIG. 6 is a front perspective view thereof.

The dashed lines within the Figures represent stitching.

The shade lines within the Figures show contour and not surface ornamentation.
